UNITED STATES PATENT OFFICE.

WILLIAM WUERZ, OF NEW YORK, N. Y.

IMPROVEMENT IN LAMP-LIGHTING APPARATUS.

Specification forming part of Letters Patent No. 130,000, dated July 30, 1872.

Specification describing certain Improvements in Lamp-Lighting Apparatus, invented by WILLIAM WUERZ, of the city and county of New York and State of New York.

Nature and Object of the Invention.

The nature and object of my invention are to produce an apparatus for lighting lamps or lanterns which at the same time opens (or shuts) the stop-cock and ignites the escaping gas without requiring the person performing the work to either climb up to the lamp or lantern or to carry ladders or other kind of steps with him, thus performing the work in the shortest possible time.

SPECIFICATION.

In the drawing, Figure 1 represents a longitudinal section of the lamp-lighting apparatus; Fig. 2, front view thereof; Fig. 3, side view thereof.

Similar letters of reference indicate corresponding parts in the drawing and specification.

A is a pipe, tube, hollow pole, or handle. B is a rod with teeth, *f*, to move the key or wrench C. *g* is a knob which projects through the slot *i* to move the rod B; C, the key or wrench, constructed as shown in drawing, may be of suitable length and size to fit the purpose. *d* is the cross-hole in the key or wrench, shaped to fit the stop-cock, which the instrument is intended to open and shut; *e*, teeth in the shaft of the key or wrench, by which the same is turned one-fourth of a circle, or more, if desirable. E is the box or frame in which the key or wrench revolves. F is a ring with a set-screw to secure the key

in the frame E. G is a pipe or tube fastened on the top of frame E, in which the rod B moves. L is a lamp or torch secured to the upper end of rod B. K is a cover to prevent the lamp or torch from being extinguished by wind, rain, or other outside influences. Lamp L is, when the knob *g* is pushed upward, raised to the upper end of tube G, and, also, at the same time and by the same motion, the key or wrench C opens the stop-cock *z* of the lamp or lantern, which, being lighted, will readily set fire to the then escaping gas. Instead of the tube G a solid stem of wood may be fastened to the upper part of the frame E, and the lamp or torch L be secured to its upper end, with the cover to protect the same; but when this is adopted the rod B will end when passing through the upper side of frame E. When the lamp or lantern shall be extinguished, the stem with torch may be unscrewed and not carried with the instrument. Knob *g* is to be pushed upward before setting the cross-hole *d* on the stop-cock *z* and then pulled downward, thus closing the stop-cock.

Having thus described my invention, what I claim as new, and desire to secure by Letters Patent is—

1. The combination of the tube A, rod B, frame E, and wrench C, constructed and arranged to operate as described.

2. I claim the movable torch L, in combination with sliding rod B and toothed portion *e* in wrench C, substantially as described and shown.

WM. WUERZ.
